US0D1030107S

(12) **United States Design Patent** (10) **Patent No.:** **US D1,030,107 S**
(45) **Date of Patent:** **** Jun. 4, 2024**

(54) **LIGHTING DEVICE**

(71) Applicant: **Energizer Brands, LLC**, St. Louis, MO (US)
(72) Inventors: **Angelo Kotsis**, Marrickville (AU); **Timothy James Rugendyke**, Woy Woy (AU); **Chi Keung Lee**, Merrylands (AU); **William Narpes**, North Ridgeville, OH (US)

(73) Assignee: **Energizer Brands, LLC**, St. Louis, MO (US)

(**) Term: **15 Years**

(21) Appl. No.: **29/799,863**

(22) Filed: **Jul. 16, 2021**

(51) LOC (14) Cl. **26-02**

(52) U.S. Cl.

USPC **D26/39**

(58) **Field of Classification Search**

USPC **D26/37-41; D10/111, 114.9**
CPC **F21Y 2115/00; F21Y 2113/00; F21Y 2105/00; F21Y 2107/00; F21V 23/0414; F21V 23/003; F21V 21/0816; F21V 14/065; F21V 15/01; F21V 17/02; F21V 21/096; F21V 21/088; F21V 21/084; F21V 14/025; F21V 14/045; F21V 17/007; F21V 17/12; F21V 23/007; F21V 23/0492; F21V 33/0008; F21V 33/0084; F21V 5/006; F21V 7/0075; G08B 21/043; F21L 4/00**

(57) **CLAIM**

The ornamental design for a lighting device, as shown and described.

DESCRIPTION

FIG. 1 is a top front perspective view of a lighting device shown with environment;

FIG. 2 is a top front perspective view thereof, shown without environment;

FIG. 3 is bottom rear perspective view thereof;

FIG. 4 is a front view thereof;

FIG. 5 is a back view thereof;

FIG. 6 is a left side view thereof;

FIG. 7 is a right side view thereof;

FIG. 8 is a top view thereof; and,

FIG. 9 is a bottom view thereof.

The broken lines are directed to unclaimed features of the lighting device and environment. The broken lines form no part of the claimed design.

1 Claim, 9 Drawing Sheets
